UNITED STATES PATENT OFFICE.

EDWARD S. STIMPSON, OF HOPEDALE, MASSACHUSETTS, ASSIGNOR TO
DRAPER COMPANY, OF HOPEDALE, MASSACHUSETTS, A CORPOR-
ATION OF MAINE.

FILLING-REPLENISHING LOOM.

SPECIFICATION forming part of Letters Patent No. 718,587, dated January 13, 1903.

Application filed December 11, 1901. Serial No. 85,486. (No model.)

To all whom it may concern:

Be it known that I, EDWARD S. STIMPSON, a citizen of the United States, and a resident of Hopedale, county of Worcester, State of Massachusetts, have invented an Improvement in Automatic Filling - Replenishing Looms, of which the following description, in connection with the accompanying drawings, is a specification, like characters on the drawings

10 representing like parts.

This invention relates to looms provided with automatic filling-replenishing mechanism of the type wherein the running shuttle is provided as occasion demands with a fresh 15 supply of filling, and heretofore the shuttle has been provided with an automatically-self-threading device.

In my present invention I have devised means independent of the shuttle for positively threading the same when a fresh filling-supply is inserted in the shuttle, and the latter instead of being provided with a threading device is made with a thread-delivery eye having a continuous rim. In other words, 25 such delivery-eye is merely a hole made in the side wall of the shuttle, and the filling is threaded through this eye by novel threading means, which form the main part of my invention.

30 Figure 1 is a right-hand side elevation of a portion of a loom provided with automatic filling - replenishing mechanism, the feeder thereof and the lay being shown in section and with one embodiment of my invention being applied thereto. Fig. 2 is a detail of a portion of the apparatus shown in Fig. 1, but with the shuttle-threading means in position to thread the shuttle, a fresh supply of filling having been just transferred to the latter.

40 Fig. 3 is a front elevation of the apparatus shown in Fig. 1 with the parts in the same relative position. Fig. 4 is a plan view, partly broken out, of the end of the shuttle provided with the thread-delivery eye. Fig. 5 is a 45 front elevation thereof. Fig. 6 is a perspective detail of a part of the threading means detached. Fig. 7 is an enlarged side elevation of the thread-catcher as it appears when it enters the shuttle preparatory to threading

it, and Fig. 8 is a similar view showing how 50 the thread is caught and held as the catcher is withdrawn from the shuttle.

Referring to Figs. 1 and 3, the loom-frame A, the lay A³, slotted at 10 below one of the shuttle-boxes, the bunter C² on the lay, and the filling - feeder F are of well-known construction, the two disks a' a², which support between them the filling-carriers b, being connected to rotate in unison on a stud a, rigidly secured to a stand A⁷, mounted on the breast-beam A⁴⁰, the filling ends being led over an outer disk b² (see dotted lines, Fig. 3) and thence to a holding-stud b³, said stud and the disk b² rotating intermittently to present the filling-carriers one by one in transferring position. The feeder and the means for effecting its rotation are substantially as shown in United States Patent No. 664,790, dated December 25, 1900, and need not be further described herein, as in said patent the stand A⁷ supports a horizontal stud f, on which is loosely mounted the hub f² of the transerrer f', extended between the disks of the feeder, engaging the head of the filling-carrier, while the tip of the latter is engaged by the notched 60 and downturned end 22 of a lateral arm 21, rigidly secured to the transerrer f', and a yielding tip-support f⁸ is mounted on an arm f⁷, secured to the stud f, as in said patent. The transfer of a filling-carrier to the shuttle is effected when a change occurs in the condition of the filling in the shuttle—such, for instance, as its exhaustion to a desired extent or its breakage—such a condition effecting in well-known manner the turning of 65 a rock-shaft d' in the direction of the arrow 65, the rock-shaft having fast upon it an arm d², provided with a jaw d¹⁸, a co-operating jaw d¹⁴, pivoted at d¹⁵ on the arm, (see dotted lines, Fig. 1,) being held in the position shown by a strong spring S^X, the latter also acting to normally depress the arm d², all as in United States Patent No. 677,096, dated June 25, 1901. A shuttle-feeler y^X is fulcrumed on the frame at y and is provided 90 with a pin y', which extends between the jaws d¹³ d¹⁴, the shuttle-feeler having a rigid branch y², provided with an elongated cam-

slot y^3 , entered by a lateral lug m^{14} , secured to an arm m^{13} , rigidly mounted on a stud n^x , pivoted in the lower bifurcated end of a depending arm f^3 , secured to or forming a part 5 of the transferrer-hub f^2 . A notched dog m^{15} is secured to the arm m^{13} , and when the rock-shaft d' is turned in the direction of the arrow 65, Fig. 1, the shuttle-feeler is through arm d^2 swung rearwardly into operative position, 10 and the branch y^2 acts to swing the arm m^{13} and move the dog m^{15} into the path of the bunter C^2 , the movement of the dog being thereby effected in a positive manner. When the bunter engages the dog, the transquirer 15 is depressed in well-known manner to transfer the lowermost filling-carrier in the feeder to the shuttle as the lay reaches its forward position, as shown in Fig. 2.

Referring now to Figs. 4 and 5, the shuttle 20 S , having a longitudinal opening s^x for the filling-carrier, which is held therein by suitable holding means, (not shown,) is provided with a rather large aperture s in its side wall near one end, forming the thread-delivery 25 eye, and a transverse wall s' separates the opening s^x from a smaller chamber s^2 , with which the eye s communicates. A central longitudinal depression or groove g is made in the shuttle-body in front of the chamber 30 s^2 , and a notch 6 in alignment therewith is made in the top of the wall s' . When a filling-carrier is transferred to the shuttle, its filling end, which it will be remembered is passed around the disk b^2 and fastened to 35 the stud b^3 , will enter the notch 6 and groove g , crossing the chamber s^2 , and, as will now be described, a thread-positioner engages such part of the thread and pushes it down into the chamber into position to be engaged 40 by a thread-catcher which enters the shuttle through the eye s . A lateral arm h has at its inner end a concave seat h^x , Fig. 6, to fit the hub f^2 of the transquirer, to which said arm is secured by screws 8, the outer end of 45 the arm having a socketed enlargement h' , provided with a downturned apertured ear h^2 to loosely embrace the stud f , and the thread-positioner is secured to the head and is extended rearwardly. The thread-positioner is 50 shown as a straight blade-like member k , having its rear end bifurcated and bent to present two downturned fingers $k' k'$, slightly separated and notched or concaved at their tips, as at k^2 , Fig. 6, the normal position of the thread-positioner being shown in Fig. 1, its fingers being so located that when a transfer is effected the movement of the transquirer rocks the blade-like arm k and causes the fingers k' to enter the chamber s^2 in the shuttle, the 55 notches k^2 engaging the thread and pressing it down into the chamber. This position of the thread-positioner is shown in Fig. 2, the filling-thread being omitted to avoid confusing the drawing, the deep notch 6 in the 60 wall s' of the shuttle receiving the thread as it is pushed down into the chamber s^2 . An L-shaped leg p is loosely mounted on the

stud f adjacent the head h' , the socket portion h^3 of the latter receiving the hub p^x of said leg, the latter being held in place by a 70 bent stop-finger f^{20} , secured to the stud f by a suitable set-screw 10. The foot p' of the leg p is longitudinally slotted at 12, Figs. 1 and 2, to receive a clamping-bolt 14, which passes through a thin flat extension p^2 and 75 adjustably connects it in a rigid manner with the leg, the extension being reduced in thickness toward its rear end and having its extremity turned up and forward to form a hook p^3 , which constitutes one member of the 80 thread-catcher. A coöperating member p^4 is fulcrumed at p^5 on the side of the member p^2 and has its rear end slightly upturned, as at p^6 , (see Figs. 7 and 8,) the opposite end of the member p^4 being drawn down and tempered 85 to constitute a spring p^7 , which at its extremity is bent laterally and inserted in a slot 16 in the extension p^2 , the spring normally acting to lift the tip of the member p^4 , so that it lies against the side face of the hook p^3 , as in 90 Fig. 1. The leg p is so located on the stud f that when the said leg is swung into operative position the members $p^2 p^4$ will enter the eye s of the shuttle when the lay beats up, the front wall b^{10} of the shuttle-box B^x having 95 an opening b^{12} therein to permit such movement.

Referring to Fig. 3, it will be seen that the stud n^x is bent down at n' and then laterally at n^2 , the latter portion being extended far 100 enough to pass beneath the lower edge of the extension p^2 , and as the stud n^x turns with the arm m^{13} it will be manifest that when the latter is moved to bring the dog m^{15} into the path of the bunter C^2 the part n^2 of the 105 stud will act upon the extension p^2 , swinging it and the leg p about the stud f into the position shown in Fig. 2, the bent stop-finger f^{20} limiting such movement by engaging the leg p . Of course this positioning of the 110 thread-catcher is effected before the lay beats up, so that as it comes forward, the shuttle being in the box B^x , the extremities of the members p^2 and p^4 will pass through the openings b^{12} and the eye s of the shuttle into the 115 chamber s^2 of the shuttle. A shelf b^{16} on the shuttle-box wall b^{10} at the bottom of the opening b^{12} acts upon the lower edge of the member p^4 in front of its fulcrum p^5 , tipping said member against the action of its spring end 120 p^7 , so that its tip p^6 will be depressed into the position shown in Figs. 2 and 7 and leaving the hook p^3 open. When filling transfer is effected, immediately thereafter the positioner k acts with its fingers k' upon the thread, pushing the latter down under the beak of the hook p^3 , the fingers at such time straddling said hook and the tip of its coöperating member p^4 , and as the lay begins to move back the thread is pulled completely into the hook, while the 130 transquirer and thread-positioner return to normal position. As the lay recedes the controlling-shelf b^{16} releases the member p^4 , so that its spring p^7 immediately rocks it to lift

its tip p^6 , which is beneath the filling-thread t , Fig. 8, and as the member p^4 assumes its normal position with its tip contiguous to the top of the hook p^3 the thread will be nipped between the two adjacent faces, and the bight of thread so held is pulled through the delivery-eyes of the shuttle. One end of the bight leads through the eye into the chamber s^2 and thence to the holding-stud b^8 , and the other end leads through the notch 6 to the filling-carrier in the shuttle, and when the latter is thrown across the lay the thread is broken between the stud b^8 and the thread-catcher, the thread at the other side of the latter drawing off through the notch 6 and eye s from the filling-carrier in the shuttle. After one or more picks the thread between the edge of the cloth and the thread-catcher is severed in any suitable manner, as by a thread-cutting temple.

From the foregoing description, taken in connection with the drawings, it will be seen that the shuttle-threading means is entirely independent of the shuttle and that the shuttle is positively threaded by such means. So, too, the shuttle has a thread-delivery eye with a continuous rim, as distinguished from an eye having a thread-directing slot leading thereto, the structure of the shuttle being greatly simplified and its weight decreased. These features are broadly new so far as I am aware, and accordingly my invention is not restricted to the precise construction and arrangement herein shown and described, for the same may be rearranged or modified in various particulars without departing from the spirit and scope of my invention.

When the spring S^X is free to act, it operates through the rock-shaft d' and arm d^2 to restore the shuttle-feeler y^X and the dog m^{15} to normal position, the turning of the arm m^{13} by or through the action of the cam-slot y^3 permitting the leg p and its attached thread-catching means to return to the position shown in Fig. 1.

The enlarged upper end of the cam-slot permits the movement of the dog m^{15} and its supporting-arm m^{18} when the former is engaged and moved by the bunter C^2 as the lay beats up.

Having fully described my invention, what I claim as new, and desire to secure by Letters Patent, is—

1. In a loom provided with automatic filling-replenishing mechanism, a shuttle adapted to contain a supply of filling, and means wholly independent of the shuttle to engage and position the filling end and thread the shuttle upon filling replenishment.

2. In a loom provided with automatic filling-replenishing mechanism, a shuttle adapted to contain a supply of filling, and means controlled by or through the operation of said mechanism to positively thread the shuttle when filling replenishment is effected, and to hold the thread end when the shuttle is thrown through the shed.

3. In a loom provided with automatic fill-

ing-replenishing mechanism, a shuttle adapted to contain a supply of filling, and means independent of the shuttle to automatically thread the same and temporarily hold the filling end after filling replenishment, when the shuttle is thrown through the shed.

4. In a loom provided with automatic filling-replenishing mechanism, a shuttle adapted to contain a supply of filling, and shuttle-threading means, said means including a thread-positioner, and a thread-catcher to take the thread therefrom and draw it through the delivery-eye of the shuttle, the thread-catcher positively holding the thread when the shuttle is thrown through the shed.

5. In a loom provided with automatic filling-replenishing mechanism, a shuttle adapted to contain a supply of filling, and having a delivery-eye in its side, and means independent of the shuttle, to engage and draw the filling-thread end through the delivery-eye of the shuttle upon replenishment of filling, said means thereafter holding the filling-thread end when the shuttle is thrown.

6. In a loom provided with automatic filling-replenishing mechanism, a shuttle adapted to contain a supply of filling, and having a delivery-eye in its side, and means independent of the shuttle and operative by or through filling replenishment to draw the filling-thread end through the delivery-eye of the shuttle and hold the filling end when the shuttle is thrown through the shed.

7. In a loom provided with automatic filling-replenishing mechanism, a shuttle adapted to contain a supply of filling and having a thread-receiving chamber and a side delivery-eye communicating therewith, and a transverse wall separating the chamber from the supply of filling, and means operative upon filling replenishment to insert the filling end into the chamber of the shuttle and to draw the same out through the delivery-eye, thereby thread the shuttle.

8. In a loom provided with automatic filling-replenishing mechanism, means to control the time of its operation, a shuttle adapted to contain a supply of filling, and threading means for the shuttle, governed by or through the controlling means, to positively thread the shuttle upon filling replenishment and to hold the filling end when the shuttle is thrown through the shed.

9. In a loom, automatic filling-replenishing mechanism, including a transfer, a shuttle adapted to contain a supply of filling and having a side delivery-eye, controlling means for said mechanism, a thread-positioner movable with the transfer to depress the filling end into the shuttle when a fresh supply of filling is transferred thereto, and thread-catching means to enter the shuttle through its delivery-eye, and engage and withdraw the filling depressed by the thread-positioner.

10. In a loom provided with filling-replenishing mechanism including a transfer, a shuttle adapted to contain a supply of filling

and having a side delivery-eye, a shuttle-feeler, and means controlled jointly by the transerrer and shuttle-feeler to automatically thread the shuttle upon filling replenishment.

11. In a loom provided with filling-replenishing mechanism including a transerrer, a shuttle adapted to contain a supply of filling and having a side delivery-eye, a shuttle-feeler, and means to automatically thread the shuttle upon filling replenishment, said means including a thread-positioner governed by the transerrer, and a thread-catcher governed by or through the shuttle-feeler.

12. In a loom provided with filling-replenishing mechanism, the lay having a shuttle-box with an apertured front wall, a shuttle adapted to contain a supply of filling and having a delivery-eye to register with the aperture when the shuttle is boxed, threading means for and independent of the shuttle and operated by or through filling replenishment, said means including a two-part thread-catcher the parts of which are normally closed, and a device on the lay to open said parts as they enter the shuttle, in readiness to engage the filling-thread.

13. In a loom, a shuttle having a side delivery-eye, shuttle-threading means including a bifurcated positioner to engage and depress the filling end into the shuttle, and a thread-catcher including a hooked member and a co-operating holding member, and means to move said members into the shuttle through its delivery-eye to engage the filling end between the forks of the positioner and withdraw it through the delivery-eye.

14. In shuttle-threading means for looms, a thread-positioner to place the filling end in

position, a thread-catcher comprising a hooked member and a co-operating holding member pivotally connected therewith, means to normally hold said members closed, and a device to temporarily open them to engage the filling end when in position.

15. In a loom provided with automatic filling-replenishing mechanism including a transerrer, means to control the time of operation of said mechanism, a shuttle adapted to contain a supply of filling and having a side delivery-eye, a thread-positioner operatively connected with and moved by the transerrer to position the end of a freshly-transferred filling-supply in the shuttle, and a swinging thread-catcher operatively moved by or through the controlling means to enter the delivery-eye of the shuttle, engage and withdraw through said eye the positioned filling end, and thereafter hold it when the shuttle is thrown through the shed.

16. In a loom provided with automatic filling-replenishing mechanism, a shuttle provided with a chamber and adapted to receive a supply of filling and having in its side a delivery-eye with a continuous perimeter, communicating with the chamber in the shuttle, and threading means to depress the filling end into the shuttle-chamber and to engage such depressed portion of the filling end and withdraw it from the chamber through the delivery-eye, to thereby thread the shuttle.

In testimony whereof I have signed my name to this specification in the presence of two subscribing witnesses.

EDWARD S. STIMPSON.
